C. R. KEERAN

AUTOMATIC PENCIL

Filed June 4, 1924

51 Inventor
Charles R. Keeran
By Chas. M. H. Day

UNITED STATES PATENT OFFICE.

CHARLES R. KEERAN, OF CHICAGO, ILLINOIS.

AUTOMATIC PENCIL.

Application filed June 4, 1924. Serial No. 717,686.

To all whom it may concern:

Be it known that I, CHARLES R. KEERAN, a citizen of the United States, and resident of Chicago, in the county of Cook and State 5 of Illinois, have invented certain new and useful Improvements in an Automatic Pencil, of which the following is a specification.

My invention relates to automatic pencils 10 and particularly to an improvement in the pencil constructions illustrated in the pending applications of Deli, Ser. No. 444,956, filed Feb. 14, 1921; Keeran, Ser. No. 512,412, filed Nov. 3, 1921, and Keeran and 15 Lynn, Ser. No. 548,273, filed March 31, 1922.

An object of my invention is to provide a pencil having large capacity for utilizing long leads, that is, leads approximately two inches in length.

20 This result is secured by eliminating all division walls in the lead chamber and lessening the diameter of the plunger head which travels to the upper end of the pencil body. The diameter of the plunger head 25 is lessened by adopting the expedient of increasing the number of flat sides thereof, it being preferably pentagon in cross section instead of duplex or triplex as heretofore disclosed.

30 Another object is to increase the strength of the pencil body and enhance its beauty particularly where the body is composed of a composition material such as bakelite or redmanol, the result being secured by 35 increasing the number of flat sides so that the body becomes more nearly circular. Preferably the body is decagon.

A further object is to simplify the construction in order that the steps in the 40 process of manufacture and assembling may be easily and economically performed.

A further object is to improve the construction of the means employed for projecting the eraser from its seat after the 45 outer portion becomes worn.

The invention will be more readily understood by reference to the accompanying drawing, wherein,

Fig. 1 is a longitudinal vertical sectional view through a pencil constructed in accordance with my invention;

Figs. 2 and 3 are sectional views on the lines 2—2, 3—3, respectively, of Fig. 1;

Fig. 4 is a longitudinal sectional view 55 through a pencil of similar internal construction, but in which the body or barrel is composed of metal instead of bakelite, as in the case of the construction shown in Fig. 1;

Figs. 5 and 6 are sectional views on the 60 lines 5—5, 6—6 respectively of Fig. 4, and,

Fig. 7 is a sectional view, taken on the same line as that of Fig. 2, and showing a modified form of magazine construction 65 in which large or checking leads are employed.

In the drawings and referring particularly to Fig. 1, I have illustrated a pencil body 10, which may be composed of bakelite, redmanol or wood, the body being 70 preferably decagonal in cross section. By increasing the number of sides the body is more nearly circular in cross section and the beauty and strength are increased. The body is axially molded or bored to provide recesses 11, 12, 13 of three diameters. The recess 11 is circular and the largest 75 in diameter; the recess 12 is the smallest in diameter and is preferably pentagon in cross section, while the recess 13 may be 80 circular in cross section.

The lower end construction is identical with that disclosed in prior applications such as those hereinabove identified and consists of a tip having a tapered portion 85 14 and a cylindrical portion 15, which fits over the reduced end 16 of the body. Fixed to the interior of the tip is the threaded tube 17, the threads being formed by rolling the same in the tube. Within the tube 90 17 is a plunger consisting of the stem 18 having projections 19 thereon, which act as threads for engagement with the tube, and the head 20, preferably pentagon in cross section. It will be noted that the 95 tip together with the attached tube and

contained plunger may be bodily removed longitudinally from the pencil body in any position of adjustment of the parts.

The means for guiding the plunger head and preventing it from turning consists of a tube having a reduced pentagon portion 22. The large portion 21 securely fits the pentagon recess 12, the fit being such that it is necessary in assembling to drive the tube in place. The lower end of the portion 21 is surmounted by a flange 23, which limits the upward movement when the parts are being positioned. The portion 22 of the tube has an internal diameter only 15 slightly greater than that of the head 20 of the plunger; thus the plunger may freely reciprocate in the space but is prevented from turning therein. The walls at the juncture of the portions 21, 22 of the tube 20 are tapered in order to facilitate the entering of the plunger into the tube 22. It will be noted that the tube 22 is unsupported except at the point of engagement with the body at the upper end of the recess 12; 25 thus no transverse walls interfere with the lead magazine 24, which surrounds the guide tube 22.

It will be noted that the upper end of the tube 22 is contracted as at 25, to an extent 30 sufficient to prevent the head 20 from passing out at the upper end. However, I provide a circular extension 26 on the upper end of the plunger above the head, and shape the opening 27 at the upper end of the tube 35 22 to admit this extension. However, the opening is of a diameter less than the diameter of the lead so that a user cannot by mistake place a lead in the upper end of the tube. However, the projecting portion 26 40 of the plunger may engage the transverse portion 28 of an eraser holder, the sides 29 of which grasp an eraser 30 and hold the same within the reduced upper end 31 of the ferrule 32.

45 In the event the eraser becomes worn to an extent necessitating ejection to present another portion, or removal for the purpose of replacement, the plunger is retracted by rotating the tip relative to the pencil body 50 until the portion 26 of the plunger projects through the upper end of the tube and contacts the lower wall of the eraser holder. Continued rotation will serve to eject the eraser to a point at which it may be grasped 55 by the fingers. Preferably I provide a cap 33 for decorative purposes, the upper portion of which may be flared if desired, and the lower portion of which is cylindrical and of substantially the same diameter as 60 the ferrule 32.

In the construction shown in Figs. 4 to 6 inclusive, the tip 34, attached lead tube 35, plunger 36, plunger head 37 and plunger extension 38 are identical with those heretofore described. This is likewise true of the

ferrule 39, cap 40, and eraser holder 41. The body construction is, however, slightly different and comprises a metal barrel 42, within the lower end of which a sleeve 43 is telescoped, the sleeve projecting beyond 70 the lower end of the barrel, and being fixed to the tip 34. The sleeve has a concentric reduced lower end 44, which receives the extremity of a metal tube having three 75 diameters. The lower portion 45 is circular in cross section and the largest in diameter. The portion 46 is pentagon in cross section and fits within a similarly shaped recess 47, concentric of a flanged disc 48, soldered to the inner surface of the barrel 42. The upper portion 49 of the tube is likewise pentagon and the smallest in diameter. This upper portion serves as a guide for the head 37 of the plunger.

The operation of the two forms of the invention is the same. Rotation of the tip relative to the body results in advancing or retracting the plunger in accordance with the direction of rotation of the plunger.

As a lead is worn off at the point the plunger head finally reaches the enlarged portion of the tube, this being the portion 21 in Fig. 1 and the portion 46 in Fig. 4, at which point the plunger head may rotate freely and continued relative rotation of the tip and body results in no further advancement of the plunger. Thereafter the tip and attached parts are removed from the lower end of the body, the plunger retracted and a reserve lead inserted in the threaded tube. Upon replacement of the plunger and reassembling of the parts the pencil is again ready for operation. Access to the reserve leads is secured by removing either the eraser or the ferrule from the upper end of the pencil.

It will be noted that the parts are so proportioned that the plunger cannot be retracted to a point at which the threads are disengaged from the tube. Thus it is always possible to remove the plunger with the tip. Of course it will be understood also that in ejecting the eraser from the ferrule by which it is held, the action of the plunger, the resistance to the thrust of which is on the tip, may result in displacing the tip downwardly instead of the eraser upwardly. In that event a pressure of the point of the tip on a flat surface and the exerting of a downward pressure on the body will result in displacing the eraser upwardly with the return of the tip to its seat.

The advantage in the suggested constructions from the standpoint of manufacture will be apparent. In the construction of Fig. 1, the assembling operation consists merely in inserting the guide tube and forcing the same into tightly fitting relation with the internal walls. The mounting of the cap and ferrule completes the assem-

bling. This is likewise true of the construction of Fig. 4, except that the disk 48 is soldered in position and the tube then inserted. In the construction of the body 5 shown in Fig. 1, it is contemplated that the molding operation will result in the completed body having the recesses of the shape desired.

In the construction of Fig. 7 provision is made for the accommodation of a plurality of larger size leads such as used in checking and this is accomplished without weakening the body structure in the molded pencil. The result is accomplished by providing the body 49 with a number of semi-circular grooves 50, corresponding to the number of sides on the guide tube 51. In this case, the tube being pentagonal in cross section, there are five of the grooves provided. These may readily be molded in the formation of the body and the ridge of material at the point 52 between the grooves furnishes the requisite strength to offset the grooves in the body. By this means a plurality of much larger leads may be accommodated.

Obviously the construction is capable of some modification and I do not wish to be limited except as indicated in the appended claims.

I claim:

1. In a pencil, a body, means providing an axial, non-circular recess at a point intermediate the ends of the body, a tube having 35 two portions of different diameters, both portions being non-circular in cross section, the portion of the larger diameter tightly fitting said non-circular recess, and lead feeding means including a plunger having 40 a non-circular portion non-rotatable and slideable in the smaller of the non-circular portions of said tube.

2. In a pencil, a body having a bore constituting a lead magazine, said bore being contracted at a point substantially midway of the length of the body to form a non-circular recess, a tube having two portions of different diameters, both portions being non-circular in cross section, the portion of 50 the larger diameter tightly fitting said non-circular recess, and lead feeding means including a plunger having a non-circular portion non-rotatable and slideable in the smaller of the non-circular portions of said tube.

3. In a pencil, a body having an axial bore from end to end thereof, a portion of the bore of limited length at a point substantially midway between the ends thereof being of non-circular outline in cross section, a tube having portions of different diameters, both portions being non-circular in cross section, the portion of larger diameter cooperating with and snugly fitting the 60 non-circular portion of said bore, and a

lead feeding plunger having a head which is non-circular in cross section and of a diameter to enter the portion of smaller diameter of said tube without the capability of rotation therein, said head being capable 70 of rotation in the portion of larger diameter of said tube.

4. A pencil comprising in combination a body having a longitudinal axial opening from end to end thereof, the portion of said opening substantially midway of the length of the tube being of angular cross section and of less diameter than another portion of said opening, a guide tube having portions of two diameters, both of said portions being polygonal in cross section, the portion of larger diameter cooperating with the said constricted portion of the longitudinal opening, and a lead advancing plunger having a head of polygonal cross section, adapted 80 to rotate in the portion of said tube of larger diameter and prevented from rotation in the portion of said tube of smaller diameter.

5. A pencil comprising in combination a body having a longitudinal axial opening from end to end thereof, the portion of said opening substantially midway of the length of the tube being of angular cross section and of less diameter than another portion 90 of said opening, a guide tube having portions of two diameters, both of said portions being polygonal in cross section, said tube being open from end to end, the portion of larger diameter cooperating with the said constricted portion of the longitudinal opening, and a lead advancing plunger having a head of polygonal cross section, adapted 95 to rotate in the portion of said tube of larger diameter and prevented from rotation in the portion of said tube of smaller diameter.

6. A pencil comprising in combination a body having a longitudinal axial opening from end to end thereof, the portion of said opening substantially midway of the length of the tube being of angular cross section and of less diameter than another portion of said opening, a guide tube having portions of two diameters, both of said portions being polygonal, said tube being open from 100 end to end, the open upper end being constricted to a diameter less than the diameter of a lead, the portion of larger diameter cooperating with the said constricted portion 105 of the longitudinal opening, and a lead advancing plunger having a head of polygonal cross section, adapted to rotate in the portion of said tube of larger diameter and prevented from rotation in the portion of said tube of smaller diameter.

7. In a pencil, the combination of a body having a longitudinal bore of three diameters, the portion at the upper end being of greatest diameter and constituting a lead magazine, the portion at the lower end being 110

of less diameter and shaped to receive a lead tube the intermediate portion of the bore being of least diameter and of angular cross section, a guide tube having portions of two diameters, the portion of the larger diameter being of angular cross section and fitting the intermediate portion of the bore of smallest diameter, the portion of the tube of the smaller diameter being of polygonal cross section and projecting centrally of the lead magazine, and a lead advancing plunger having a head of polygonal cross section the diameter of which is proportioned to enable the head to rotate in the larger of the two diameters of said tube and to be received and be prevented from rotation in the tube of the smaller diameter.

8. A pencil comprising in combination a body having an axial bore open from end to end, a portion of the bore substantially midway between the ends of the body being of angular cross section, a guide tube open from end to end and having portions of two diameters, the portion of the larger diameter being of angular cross section and snugly fitting the intermediate portion of the bore, the lower end of said tube being provided with a lateral projection adapted to act as a means for limiting the upward movement of the tube, and a lead advancing plunger adapted to cooperate with said tube.

9. A pencil comprising in combination a body having an axial bore open from end to end, a portion of the bore substantially midway between the ends of the body being of angular cross section, a guide tube open from end to end and having portions of two diameters, the portion of the larger diameter being of angular cross section and snugly fitting the intermediate portion of the bore, the lower end of said tube being provided with a lateral projection adapted to act as a means for limiting the upward movement of the tube, and a lead advancing plunger adapted to cooperate with said tube, the upper end of said tube being constricted to a diameter less than the diameter of a lead to be used in said pencil.

10. In a pencil, the combination of a body having a guide tube, a plunger having a head cooperating with said tube, said tube being provided with a constricted portion at its upper end and said plunger being provided with a portion of smaller diameter above the head, said constricted portion of the tube preventing the head from passing therethrough but permitting the upper extension therefrom to pass through, and an eraser slidably mounted in the upper end of the pencil and adapted to be displaced outwardly by movement of the plunger.

11. In combination, a pencil body having a guide tube fixedly mounted therein, a plunger, screw means for reciprocating the

plunger without rotation, the plunger having a head cooperating with said tube and provided with an upper extension from said head of less diameter than the head, the upper extremity of the tube being constricted to prevent the exit of the plunger head therefrom and permitting the extension to pass therethrough, and an eraser frictionally held in the upper end of the pencil and adapted to be displaced upwardly to the extent of the extension on the plunger.

12. In a pencil, the combination of a body having a longitudinal bore open from end to end thereof, the portion of the bore at the upper end being of the largest diameter and constituting the lead magazine, a portion of the bore substantially midway between the ends of the body being of the smallest diameter and of non-circular cross section, a tube having a portion of non-circular cross section cooperating with the intermediate portion of the bore and projecting centrally of the lead magazine, said upper portion of the tube constituting a guideway for a plunger head, said tube approaching circular form in cross section and having a flat side, and lead advancing means comprising a tip and attached threaded tube, and a plunger having a head shaped to correspond to the cross section of the upper portion of the guide tube, said lead feeding means being removable bodily from the lower end of the pencil.

13. In a pencil, the combination of a body having an axial bore of three diameters, a tip removably fitted on the lower end of the body, a threaded tube fixed to the tip, a plunger cooperating with the threaded tube, a ferrule at the upper end of the body, an eraser slidably held in said ferrule, the portion of the bore at the upper end being of largest diameter and constituting a lead magazine, the portion of the bore at the lower end being of less diameter and capable of freely admitting the threaded tube, the intermediate portion of the tube being of least diameter and of angular cross section, a guide tube having portions of two diameters, both portions being angular in cross section, the portion of larger diameter snugly fitting the intermediate portion of the bore, the portion of smaller diameter of said tube projecting centrally of the lead magazine, the plunger having a head cooperating with said portion of smaller diameter of said guide tube, said head being freely rotatable in the portion of the guide tube of the larger diameter, said guide tube having an open upper end and the plunger being adapted to project through said open upper end and displace said eraser.

14. In a pencil, the combination of a body having an axial bore open from end to end of the body, the upper portion of the bore

being of the largest diameter and constituting a lead magazine, a portion of the bore midway of the body being of the smallest diameter and of non-circular cross section, and a guide tube of two diameters, the portion of the largest diameter being fitted into the bore at the point of its smallest diameter, the upper portion of the tube approaching the circular in cross section and having

a plurality of flat sides, said upper portion of the tube being unsupported in the lead magazine, and lead feeding means including a plunger having a head of a cross section corresponding to the cross section of the upper portion of said tube.

Signed at Chicago, Ill., this 2nd day of June, 1924.

CHARLES R. KEERAN.
